UNITED STATES PATENT OFFICE.

RICHARD REEDER, OF BUTLER, PENNSYLVANIA.

STORM-CURTAIN FOR VEHICLES.

SPECIFICATION forming part of Letters Patent No. 702,480, dated June 17, 1902.

Application filed December 7, 1901. Serial No. 85,035. (No model.)

To all whom it may concern:

Be it known that I, RICHARD REEDER, a citizen of the United States of America, residing at Butler, in the county of Butler and State 5 of Pennsylvania, have invented certain new and useful Improvements in Storm-Curtains; and I do hereby declare the following to be a full, clear, and exact description thereof, reference being had to the accompanying drawings, which form a part of this specification.

My invention relates to certain new and useful improvements in storm-curtains for use on buggies and other vehicles having a top. This curtain is attached to the front of the 15 vehicle, as will be more particularly explained hereinafter.

In the accompanying drawings, Figure 1 is a rear view of the curtain as it will appear when in position on the vehicle. Fig. 2 is a 20 modified view of a means of attaching the curtain to the roof of the vehicle. Fig. 3 is a side view of a spring device for locking the pivoted brace portion when extended. Fig. 4 is an enlarged view of the joining-sleeve 25 used in the brace C. Fig. 5 is a view of the plan I prefer to use in attaching the curtain to the carriage-roof.

In the drawings, A represents the storm-curtain.

30 a a are windows.

a' is an arm opening in the curtain. a² is the opening in the same for the lines.

B B are cross braces or straps, having hooks b at either end to attach curtain to the 35 rights of the buggy-top.

C C are iron braces placed vertically on the curtain and securely fastened to the same by any suitable means. These braces are made in two parts and are united near the center 40 by the sleeve c. In these sleeves are slots c⁶, in which to operate the set-screw c'.

C' is the pivoted portion of the brace C, being pivoted to the lower part at c³. In Fig. 1 this extension part will be seen when connected with the upper part of the brace C and will also be seen disconnected. When it is connected and the sleeve c is drawn down and the extension part C' is made to enter the same, then to further strengthen the brace 45 50 I provide a spring B', fastened to the extension part C' at B'. At the upper end of the spring B' is a prong made at right angles with

the spring to enter a hole in the part C' and into the brace C. This spring serves as a locking device to hold the brace rigid when 55 in position.

The lower ends of the braces C terminate in a forked device for attaching the curtain to the upper edge of the dashboard. This is effected by the fork slipping down over the 60 board, the part c⁴ on one side and the spring-shaped part c⁵ on the other side. The mode of attachment at the top will be by the device shown in Fig. 5, as that shown in Fig. 2 is a modification of the attaching device as 65 shown in Fig. 5. In the latter the upper end of the brace C terminates in a bent portion c², that rests on the top E of the carriage, and the part c' is made in the form of a spring secured to the brace C and intended to snap 70 under the bow of the carriage-top and in this way hold the curtain securely in position.

In Fig. 2, E is the top of the carriage. e is a hood; D, a spring fixed to the under side of the carriage-top. This spring has two 75 parts d and d', and between these two parts the upper end of the brace (having a head c²) is made to enter and is there held by this spring. This I show as a modification of the attaching device as seen in Fig. 5.

When the curtain is in place on the carriage, the lines pass through the opening a², and when the driver has need to use his whip he can thrust his arm through the opening a'. Both of these openings will be closed by 85 a flap. The openings a a will have the usual glass covering to see through, and these lights will be securely fastened to the curtain and held in position by means of any suitable means.

The storm-curtain such as I have described can be speedily and conveniently put in position from the inside of the carriage or buggy, thus having an advantage over other curtains.

One advantage in making the braces C in section is that the curtain when not in use may be folded up into a small and convenient package and be stored away under the seat.

Having thus shown and fully described my invention, what I claim as new, and desire to secure by Letters Patent of the United States, is—

1. In a storm-curtain for buggies or carriages, the combination of the curtain A, braces B fixed crosswise on the same and the upright braces C two or more in number, 5 having the two parts C each and the connecting parts C' and the sleeves c, substantially as described and shown.
2. In a storm-curtain for carriages, the braces C, having at the upper end the hooked 10 extension e² and spring e' to attach to the buggy-top, and the forked extension c⁴ with spring c⁵ to attach the curtain to the dash- board; and the braces B terminating in hooks b to attach the curtain to the uprights of the buggy-top; all combined and arranged, substantially as described and shown. 15
- In testimony whereof I have hereunto affixed my signature in the presence of two subscribing witnesses.

RICHARD REEDER.
